JOSEPH VACCARO, OF BRISTOL, RHODE ISLAND; PIETRO VACCARO ADMINISTRATOR
OF SAID JOSEPH VACCARO, DECEASED.

TRANSPOSING DEVICE.

1,096,651.

Specification of Letters Patent.

Patented May 12, 1914.

Application filed January 22, 1913. Serial No. 743,476.

To all whom it may concern:

Be it known that I, JOSEPH VACCARO, a subject of the King of Italy, and a resident of Bristol, in the county of Bristol and State of Rhode Island, have invented a new and Improved Transposing Device, of which the following is a full, clear, and exact description.

The invention relates to pianos and its object is to provide a new and improved transposing device arranged to permit the player to quickly and accurately change the connection between the keys of the piano action to allow playing of the piano a half tone, a whole tone or several tones higher or lower than the one to which the piano is ordinarily tuned.

In order to accomplish the desired result, use is made of a shiftable connection interposed between the keys and the abstracts of the piano action so that on actuating the connecting device the abstracts are connected with the different keys to allow of playing the piano a half tone, a whole tone or several tones higher or lower than the one to which the piano is ordinarily tuned. Use is also made of a locking device for engagement with the rear ends of the keys to hold the same in lowermost position, and operating means for the said locking device and forming a locking device for the said shiftable connection.

A practical embodiment of the invention is represented in the accompanying drawings forming a part of this specification, in which similar characters of reference indicate corresponding parts in all the views.

Figure 1 is a cross section of the transposing device as applied; Fig. 2 is an enlarged sectional plan view of the same on the line 2-2 of Fig. 1; Fig. 3 is a cross section of a modified form of the transposing device as applied; and Fig. 4 is a sectional plan view of the same on the line 4-4 of Fig. 3, part being broken out.

On the piano casing A is mounted the keybed B provided with keys C, and in the casing is arranged the usual piano action D having abstracts D', wippens D², jacks D³ and hammers D⁴ for sounding the piano strings E. To the lower ends of the abstracts D' are pivoted levers F extending forwardly above the keys C and having their forward ends fulcrumed at F' on a

rail G mounted to slide on a bar H attached at its ends to the sides of the piano casing A, as plainly indicated in Fig. 2. Each lever F is provided with a capstan screw I provided at its lower end with a round head I' adapted to rest on top of a key C near the rear end thereof so that when a key C is pressed by the player an upward swinging movement is given to the corresponding lever F whereby the abstract D' connected with this lever F is raised to actuate the hammer D⁴ with a view to sound the corresponding string E.

The sliding rail G is connected by a link J with a transversely-extending hand lever K fulcrumed at its rear end at K' on the lower flange or extension rail D⁵ of the piano action. The forward end of the lever K passes through an opening A' formed in the front A² of the piano casing A, and the said hand lever K is provided at its outer end with a handle K² within convenient reach of the player. The outer end of the hand lever K engages one of a series of notches L' formed in the lower end of a plate L pivoted at its upper end at L² to the outer face of the front A², and the plate L is provided with a handle L³ adapted to be taken hold of by the player to swing the plate L upward with a view to disengage the corresponding notch L' from the hand lever K to allow the player to shift the lever sidewise either to the right or to the left according to whether the pitch is to be raised or lowered, as hereinafter more fully explained. Normally the lever K is held against movement in either direction by the locking plate L.

The lower end of the locking plate L is pivotally connected with a transverse link N extending through the opening A' and connecting at its rear end with an arm O' rising from a cam O located in the rear of the key C and fulcrumed at its ends at O² in brackets P attached to the bottom of the keybed B. The forward portion of the cam O is adapted to engage the rear ends of the keys C at the time the plate L is swung upward to unlock the lever K, as previously explained, so that the rear ends of the keys C are pressed downward and held in lowermost position during the time the lever K is shifted and with it the rail G carrying the pivots F' of the levers F. It is understood that when the plate L is swung up-

ward and the player swings the hand lever K to the right or left until the next notch L' is reached, then a sliding movement is given to the rail G to move the lever F in 5 such position that its capstan I engages the next key either to the right or to the left of the one previously engaged, so that when the keys are subsequently played the pitch of the piano is raised or lowered a half tone; 10 if it is desired to raise or lower the pitch of the instrument a whole tone, then the lever K is shifted the distance of two notches L' either to the right or to the left; and for changing the pitch several tones, the lever K 15 is shifted a corresponding number of notches L' either to the right or to the left. It is understood that by shifting the lever K the rail G is moved a corresponding distance to shift the levers F so that the capstans I engage the corresponding keys to 20 raise or lower the pitch a half tone, a whole tone or several tones as the case may be. When the desired change has been made the plate L is returned to lowermost position to 25 lock the lever K against movement and to cause the cam O to release the rear ends of the keys C to permit the player to play the keys in the usual manner.

In the modified form shown in Figs. 3 and 30 4, the keys C' are pivoted at their rear ends to flanges Q on a separate rail R arranged in the piano casing A³, and in this case the levers F² are pivotally connected at their rear ends at F² on the keybed B directly under the lower ends of the abstracts D', and the forward ends of the levers F² are provided with capstan screws I² engaging the under sides of the keys C' at a point intermediate the front and rear ends thereof. 35 The levers F² are fulcrumed on a rail G' mounted to slide on the upper face of the bottom of the keybed B, and the said rail G' is provided with a depending pin G² engaging a hand lever K³ fulcrumed at its rear 40 end at K⁴ on the bottom board of the keybed B. The forward or handle end K⁵ of the hand lever K³ is within convenient reach of the player to permit the latter to shift the rail G' whenever it is desired to change the 45 position of the levers F² relative to the keys C'. It is understood that when a key C' is played the corresponding lever F² is actuated to move the abstract D' upward with a view to cause the corresponding hammer D⁴ 50 of the piano action to sound the corresponding string. When it is desired to raise or lower the pitch of the instrument, it is only necessary for the operator to shift the hand lever K³ to the right or to the left with a 55 view to shift the levers F² so that the capstans I² engage different keys C'.

The transposing device shown and described is very simple and durable in construction, and can be readily arranged or applied to pianos as now in use.

Having thus described my invention, I claim as new and desire to secure by Letters Patent:

1. In a piano, the combination with a frame having a slot in its front, of keys, a piano action having abstracts, levers for raising the abstracts, the levers being positioned to engage the said keys, a rail mounted to slide and on which the said levers are fulcrumed, a hand lever pivoted at its rear end on a fixed part of the frame to swing in a horizontal plane, and a connection between the said hand lever and the said rail for shifting the latter, the lever having its handle end extending through the slot in the front of the frame.

2. In a piano, the combination with a frame having a slot in its front, of keys, a piano action having abstracts, and levers pivotally connected at their rear ends with the said abstracts and provided near their forward ends with pins for engaging the said keys, a rail mounted to slide and on which the said levers are fulcrumed, and a laterally movable hand lever pivoted at its rear end to a fixed part of the frame and connected with the said rail for shifting the said levers to connect the levers with different keys, the handle end of said lever extending through the slot in the front of the frame.

3. In a piano, the combination of keys, a piano action having abstracts and levers pivotally connected at their rear ends with the abstracts and adapted to engage the said keys, manually-controlled shifting means for shifting the said levers to connect the levers with different keys, locking means for depressing and locking the rear ends of the keys in lowermost position, and a locking device for the shifting means controlling the locking means for the keys.

4. In a piano, the combination of keys, a piano action having abstracts and levers pivotally connected with the said abstracts and adapted to engage the said keys, manually-controlled shifting means for shifting the said levers to connect the levers with different keys, a locking device for engagement with the rear ends of the keys to hold the same in lowermost position, and an operating means for the said locking device and forming a locking device for the said shifting means.

5. In a piano, the combination of keys, a piano action having abstracts, shifting levers pivotally connected with the lower ends of the said abstracts and each having a pin positioned to engage a piano key, a rail mounted to slide and on which the said shifting levers are fulcrumed, a hand lever under the control of the player, a connection between the said hand lever and the said rail to shift the latter on actuating the said hand lever, a locking cam mounted to swing and

adapted to engage the rear ends of the said keys, a plate mounted to swing and provided with notches adapted to be engaged by the said hand lever, and a link connecting the said plate with the said locking cam.

6. In a piano, the combination of keys, a piano action having abstracts, a manually controlled shiftable connection between the said abstracts and the said keys, a locking device for the said shiftable connection, means for engaging and depressing the rear ends of the keys, and a connection between the said locking device and the said means to actuate the latter when the said locking device is moved to unlock the said shiftable connection.

7. In a piano, the combination of keys, a piano action having abstracts, a shiftable connection between the said abstracts and the said keys, a hand lever controlling said shiftable connection, a locking device for the hand lever mounted to swing into locking and unlocking position, a cam mounted to swing and adapted to engage the rear ends of the said keys, and a link connecting the said locking device with an arm on the said cam.

8. In a piano, the combination with a frame having a slot in its front, of keys, a piano action having abstracts, levers for raising the abstracts, the levers being provided with pins for engaging the said keys,

a rail mounted to slide, the said levers being fulcrumed at their forward ends on said rail, a hand lever pivoted at its rear end on a fixed part of the frame, a link connecting the hand lever with the said sliding rail to shift the latter, the lever having its handle end extending through the slot in the front of the frame, and a locking plate pivoted to the outer face of the front of the frame, the locking plate having notches for engaging the hand lever to normally hold the lever against movement in either direction.

9. In a piano, the combination with a frame, of keys, a piano action having abstracts, levers for raising the abstracts and adapted to engage the said keys, a rail mounted to slide and on which the said levers are fulcrumed, a hand lever fulcrumed at the rear end to swing laterally, a connection between the hand lever and the rail to shift the latter on actuating the hand lever, and a locking plate for engaging the hand lever to normally hold it against movement in either direction.

In testimony whereof I have signed my name to this specification in the presence of two subscribing witnesses.
